UNITED STATES PATENT OFFICE.

BELLE AGNES EARL, OF CHICAGO, ILLINOIS.

DESIGN FOR AN APRON.

No. 38,379.

Specification for Design.

Patented Dec. 18, 1906.

Application filed November 5, 1906. Serial No. 342,158. Term of patent 3½ years.

To all whom it may concern:

Be it known that I, BELLE AGNES EARL, a citizen of the United States, residing at Chicago, in the county of Cook and State of Illinois, have invented a new and original Design for an Apron, of which the following is a specification, reference being had to the accompanying drawing, forming part thereof.

The figure is a plan view of an apron, showing my new design.

I claim—

The ornamental design for an apron, as shown.

BELLE AGNES EARL.
